UNITED STATES PATENT OFFICE.

CHARLEY BURNETT, OF WASHINGTON COURT HOUSE, OHIO.

BUILDING CONSTRUCTION.

1,407,250.

Specification of Letters Patent. Patented Feb. 21, 1922.

Application filed May 31, 1919. Serial No. 300,905.

To all whom it may concern:

Be it known that I, CHARLEY BURNETT, a citizen of the United States, residing at Washington Court House, in the county of Fayette and State of Ohio, have invented 5 certain new and useful Improvements in Building Construction, of which the following is a specification.

This invention relates to building construction and is designed particularly as an improved roof construction, although the invention is not necessarily limited thereto, inasmuch as the principles and structures involved may be applied with equal facility to 10 side wall and similar constructions.

The main object of my invention resides in a construction designed to be weather-proof and water-proof. By my construction, all joints are effectively closed to the 15 admission of moisture and likewise all joints are so arranged that warping or shrinking will not distort or destroy the construction in any manner. This arrangement is also designed with a view of cheapness, the same 20 being far cheaper to install when its effectiveness is considered than structures heretofore presented.

The preferred embodiment of my invention is shown in the accompanying sheet of 25 drawings, in which similar characters of reference designate corresponding parts, and in which:

Figure 1 is a view in perspective of a portion of a roof shown somewhat diagrammatically, but illustrating the principles and construction of my invention, and,

Figure 2 is an enlarged transverse cross-sectional view taken on the plane indicated by the line 2—2 of Figure 1, and

Figure 3 is an enlarged detail view disclosing particularly the construction and operative position of the burred washer element.

In these figures, I have illustrated my invention in connection with a roof, although it is to be understood that the invention is not limited thereto, as it may be applied with equal facility to side wall or other construction. In these views, the rafters are 45 designated by the reference numeral 1 and the ridge piece by the reference numeral 1^a. Between the rafters 1, I place a plurality of cross pieces 2 offset slightly from each other, as shown, so that the nails 3 may be 50 driven through the rafters and into the ends of each of the cross pieces 2. These

cross pieces and rafters I have termed a backing support, but it will also be understood that lath or cross pieces extending across the entire roof and applied on top of the rafters may be used if desired. The invention proper consists of a plurality of covering boards 4, each grooved along both its longitudinal edges in such manner as to present an inclined bottom 5 and a straight side wall 6. The inclined bottoms are each spaced slightly from the longitudinal edges of the boards to leave a short flat space, as shown at 7, and the arrangement is such that the inclined bottoms 5 are located intermediate the flat portion 7 and the straight walls 6. These boards are then assembled in closely associated relation and secured in position, as shown. After this, the grooves are covered by means of metallic V-shaped strips 8 which are shaped to snugly fit the inclined bottoms 7. These metallic strips are in turn secured in position by means of nails 9 preferably having lead washers 10 interposed between their heads and the metallic strips. The metallic strips are preferably punched for the reception of these nails prior to their application to the roof, and these punchings are formed from the inside of the strips outwardly, so as to leave upwardly projecting burred portions 11 in connection with which the lead washers must engage themselves when the attaching nails are driven home. These burred portions embed themselves in the lead washers to make the joints weather tight and water tight and in addition, these lead washers prevent direct contact of steel on steel and thus rusting is eliminated. The nails 9, as shown, are driven into the rafters 90 or cross pieces through the meeting edges of the boards and because of the V-shaped nature of the metallic strips, any shrinkage laterally of these boards will only tend to tighten the joint between the metallic strips 100 and the inclined bottoms of the grooves. In this manner, it must be apparent that a very effective joint is produced. In joining two sections longitudinally, as is shown at 12, I arrange the joints together directly over one of the cross pieces 2 and space the boards slightly from each other. Into the space thus formed, I place a suitable waterproofing compound such as a combination asphaltum and asbestos compound. These mixtures 105 may be purchased in the open market and are usually of a semi-plastic form and when

a groove is thus filled with it, a very effective water tight and weather tight joint is produced. If desired, the entire roof may be painted with similar weather proofing compound.

From the foregoing description, it will be apparent that I have provided a building construction in which all joints are effectively closed and which at the same time is comparatively cheap to produce. The joints are so formed that longitudinal shrinkage or distortion of the boards is permitted, because preferably there is no permanent connection between the metal strips 10 and the grooved edges of the boards to prevent such small relative movement as may occur during the seasoning of the boards. Any slight lateral movement or distortion which may also occur during the 15 seasoning action is permitted for the same reason, but this only increases the tightness of fit between the metal strips 8 and the boards themselves.

What I claim, is:

25 In a building structure, in combination, a backing, a pair of longitudinally extending rough forming members arranged side by side upon said backing so that their meeting

edges define a longitudinal joint, a metallic sheath strip disposed to overlie and protect 30 said joint, said strip being formed to embody a pair of outwardly diverging angularly related sides which are arranged to engage with substantially parallel faces formed upon said members, of means for 35 maintaining said sides in firm frictional relationship with said faces, consisting of a plurality of headed securing elements adapted to be embedded in said backing and formed to pass through openings provided 40 in the ridge portion of said strip, said openings being punched out to define projecting burred elements, and a plurality of relatively soft metal washers located between the heads of said securing elements 45 and strip, said washers being formed to receive said burred elements and to seal said openings when the securing elements occupy their holding positions.

In testimony whereof I affix my signature 50 in presence of two witnesses.

CHARLEY BURNETT.
